SMOKER'S APPLIANCE

Irving Florman, New York, N. Y.

Application April 3, 1934, Serial No. 718,829

5 Claims. (Cl. 312—73)

My invention relates to smoker's appliances and more particularly to a smoker's appliance adapted for table use and embodying a container for cigarettes, a lighter therefor, and an 5 ash receptacle tray.

The invention is particularly adapted for lighters of the scratch type. In such lighters a steel striker is manually drawn across a strip of flint to ignite a wick or absorbent positioned adjacent 10 the striker.

My invention for the first time embodies such a scratch type lighter in a combination cigarette container and tray. The complete arrangement, while light in weight, is so proportioned that 15 striking of the steel and igniting the lighter can be accomplished by the user with one hand and without steadyng the device with the other. Moreover, the cigarettes are retained in such a way that they may be easily withdrawn one at a time. Any tobacco which may have become 20 loosened will fall into the tray positioned beneath the container. The tray not only acts as an ash receptacle but is of such proportions as to render the arrangement stable when the lighter is operated.

25 My arrangement is easy to manufacture and assemble. It may be constructed so that the flint strip will be long enough to produce a spark when the steel is drawn across it even though very little pressure is applied, while at the same 30 time the device is neat and attractive in appearance. Lighters with short flint strips are generally unsatisfactory. They often fail to light the wick unless considerable pressure is applied, and when this is done the relatively soft flint material 35 is often ruined in a very short time. My invention avoids this disadvantage.

The objects of my invention are to effect these results and advantages mentioned.

40 Further objects and advantages of the invention will appear more fully from the following description when read in conjunction with the accompanying drawing, in which:

Fig. 1 is an elevation of the invention, a portion of the lighter being in cross-section to show the steel striker.

Fig. 2 is a top plan view of the cigarette container and lighter.

Fig. 3 is an end view of the lighter showing the flint strip in its guide groove.

50 The device, as shown in Fig. 1, consists of an ash receptacle tray 2 which serves as a base and support for the cigarette container 4 and the lighter 6. The tray 2 has a raised central portion 8 provided with an aperture 10.

The cigarette container 4 is of a height sufficient to hold about ten cigarettes 12 which may be drawn out one by one through the opening 14 which is formed by cutting off one lower corner. As shown in the plan view in Fig. 2 5 the cigarette container 4 is of a width just slightly greater than the width of a cigarette 12, so that when the container is full the cigarettes will lie horizontally one above another.

The bottom of the cigarette container 4 has 10 secured thereto an internally threaded stem 16 which supports the container 4 and the lighter 6 above the tray 2 to which it may be secured by means of a threaded bolt 18 passed through the aperture 10 in the raised central portion 8 of the 15 tray.

The lighter 6 is rigidly secured to one end edge wall 20 of the cigarette container 4. The lighter itself consists of a fuel holding casing having side walls 22, 24 and end walls 26, 28. Along end wall 28 is formed a groove 30 in which lies a strip 20 32 of flint material running from top to bottom of the lighter. In the top wall 34 of the casing is a threaded opening 36 into which screws a striker 38 having a handle or knob 40, a steel striking 25 element 42, and a wick or absorbent 44. The casing is filled with cotton or similar fuel holding material 46. Fuel may be inserted into the casing through the opening 36 when the striker 38 has been removed.

The lighter operates in the usual manner. The wick or absorbent 44 takes up fuel from the cotton 44. It is withdrawn by the handle 40 and the steel 42 is drawn along the flint strip 32 while guided by the groove 30. The sparks ignite the 30 fuel and the wick burns. By reinserting the striker the flame is extinguished. When the container 4 is of a height sufficient to hold about ten cigarettes the flint will be long enough to produce a spark and light the wick with one stroke of the 35 striker 38.

The terms "steel striker" and "flint" are used herein in their broadest sense. They are intended to define any striker element which may produce a spark when drawn across a strip of 40 material.

The cigarette container 4 and the fuel casing 45 may be made of sheet metal or tubing or can all be die cast in one piece. The tray may be of any suitable material which preferably should match the container and casing.

If the arrangement is constructed so that the size of the various elements will be relatively proportionate to their size as shown, the arrangement will not only constitute a neat and attrac- 50 55

tive smoker's appliance but will enable the lighter to be operated easily without even steadying the device. Since the flint is long the absorbent ignites easily. Moreover, since the tray has a 5 diameter somewhat greater than the width of the container and lighter combined, it is virtually impossible to tip the arrangement when operating the lighter. Still the base, and in fact the whole device, is light in weight.

10 My arrangement conveniently combines all the articles used in smoking cigarettes in the home, namely, the cigarettes and their container, the lighter, and the ash tray. The novel manner in which this is accomplished leads to the advantages mentioned above and provides an article 15 which is extremely useful and effective.

It is obvious that the tray and container arrangement described may be used with lighters of other types positioned in relatively the same 20 place. However, as mentioned above, the combination which includes a scratch type lighter has particular advantages.

Having described my invention, what I claim 25 as new and desire to secure by Letters Patent of the United States is set forth in the following claims:

- 30 1. In a device for smokers comprising an ash tray, a container comprising a dispensing cigarette compartment and a scratch lighter, said elements being combined to form a unitary structure, said container having a dispensing opening in one lower corner thereof through which cigarettes may be withdrawn from said cigarette compartment one at a time, and a second compartment within said container forming a fuel casing for said lighter, a flint strip secured to one of the walls of said container, and a striker, said container being centrally supported above and spaced from said ash tray, said ash tray being of a circumference sufficient to give said device stability and to prevent the same from being tipped over when said striker is scraped over said flint strip, said ash tray collecting tobacco clippings falling out of said dispensing 40 opening and collecting any matter scraped from said flint strip when said striker is scraped over the same and preventing said matter from burning, scorching or soiling the support on which the device rests.
- 45 2. A device according to claim 1, said fuel casing being integrally secured to said container and forming a part of said container.

3. A device according to claim 1, said fuel casing being integrally secured to said container adjacent one vertical end wall thereof and being of substantially the same height and width as said end wall, said flint strip extending substantially from the top to the bottom of said container and being secured thereto along one side thereof, said steel striker being removably inserted into and secured to said fuel casing. 5

4. A device according to claim 1, said container being of a height substantially equal to the thickness of ten cigarettes and of a thickness slightly greater than the thickness of a cigarette, said fuel casing being integrally secured to said container adjacent one vertical end wall thereof and being of substantially the same height and width as said end wall, said flint strip extending substantially from the top to the bottom of said container and being secured thereto along one side thereof, said steel striker being removably inserted into 15 and secured to said fuel casing, said ash tray having a diameter greater than any dimension of the container including the lighter.

5. A device according to claim 1, said container being of a thickness slightly greater than the 25 thickness of a cigarette of standard size and of a height sufficient to hold substantially ten cigarettes in horizontal position one above the other, said ash tray provided with a raised central portion having an aperture therein, an internally 30 threaded stem depending from said container and being integrally secured thereto, said stem being secured to said tray by a bolt passing through said aperture to support said container centrally above and spaced from said tray, said fuel casing being integrally secured to the container adjacent one vertical end wall thereof above said dispensing opening and being of substantially 35 the same height and width as said end wall, one of the vertical walls of said container having a groove therein extending substantially from the top to the bottom thereof, said flint strip secured within said groove, said casing having an opening in its top, said striker removably inserted through said opening into said casing and secured to said top, said ash tray having a diameter greater than the width of said container including 40 said casing. 45

IRVING FLORMAN.
